UNITED STATES PATENT OFFICE.

MARY LA FETRA RUSSELL, OF NEW YORK, N. Y.

DESIGN FOR A FIGURETTE.

55,959.

Specification for Design.

Patented Aug. 3, 1920.

Application filed August 30, 1919. Serial No. 320,956. Term of patent 14 years.

To all whom it may concern:

Be it known that I, MARY LA FETRA RUSSELL, a citizen of the United States of America, and resident of the borough of Manhattan, city and State of New York, have invented a new, original, and ornamental Design for a Figurette, of which the following is a specification, reference being had to the accompanying drawing, showing in Figure 1 a front view and in Fig. 2 a side view of a figurette embodying my design.

It is to be understood that my claim includes all substantial equivalents of my design as shown and described.

I claim:

The ornamental design for a figurette, substantially as shown and described.

MARY LA FETRA RUSSELL.
